UNITED STATES PATENT OFFICE.

CLINTON C. MURPHY, DECEASED, LATE OF CHICAGO, ILLINOIS; BY EDNA BLANKE MURPHY, ADMINISTRATRIX, OF CHICAGO, ILLINOIS, ASSIGNOR TO WALTER P. MURPHY, OF NEW YORK, N. Y.

CAR DOOR.

Original application filed July 13, 1918, Serial No. 244,698. Divided and this application filed May 16, 1919. Serial No. 297,535.

To all whom it may concern:

Be it known that CLINTON C. MURPHY, deceased, late a citizen of the United States, residing at Chicago, in the county of 5 Cook and State of Illinois, did invent certain new and useful Improvements in Car Doors, of which the following is a full, clear, and exact description.

This invention relates to improvements in 10 car doors, and particularly to the sliding car doors set forth in a co-pending application for Letters Patent of the United States filed July 13, 1918, Serial No. 244,698, of which this application is a division.

15 The object of this invention is to hold the door tightly against the side of the car when shut and to seal the edges thereof so that rain and dust cannot find their way around the same into the car. This is accomplished by the means hereinafter fully 20 described, and as particularly pointed out in the claims.

In the drawings:

25 Figure 1 is a side view of a portion of a freight car, including the sliding door, showing my improvements applied thereto.

Figure 2 shows an enlarged view of the lower left hand corner of the door.

30 Figure 3 is a similar view of the upper left hand corner of the same.

Figure 4 is a vertical section taken on dotted line 4—4, Figure 1.

35 Figure 5 is a horizontal view taken on dotted line 5—5, Figure 1, drawn to an enlarged scale.

Figure 6 is a transverse section of the lower left hand corner of the door, taken on dotted line 6—6, Figure 2.

40 Referring to the drawings, 6 represents the sheathing of the car side; 7 the door-frame and 8 a sliding door for closing the doorway. The edges of the door are bound by metal strips *a*, *b*, *c* and *d*, and at the corners are protected by truncated triangular shaped corner-plates *A*, *B*, *C* and *D* which constitute continuations of the protection provided for the edges of the door by said strips as well as reinforcing said corners. The lower edge of the door is protected by a special rolled metal shoe-strip *a* which, between the lower corner-plates *C* and *D* is substantially Z-shaped in cross section. The horizontal portion of this shoe-

strip constitutes the part that is secured against and protects said lower edge, and 55 the upper vertical flange of the same laps against the lower margin of the door, and the lower vertical flange depending from the inner edge of the shoe extends downward past the sill of the doorway flush with 60 the inner surface of the door. Both of the vertical and horizontal edges of said door are protected between the corners thereof by similar metal strips *b*, *c*, and *d*, respectively. The strip *b* secured to and protecting the rear edge is angle shaped in 65 cross-section, and one wing thereof laps against the rear margin of the door, and the other wing bears against the rear edge of the same and is of such width that its 70 inner edge *b'* extends beyond the inner side of said door and the projecting portion or inner edge *b'* is bent toward the rear post of the door-frame 9. The door-frame 7 projects out beyond the vertical plane of the 75 outer surface of the side of the car, and the projecting portion of the rear side of the rear post of the door-frame has a vertically disposed angle-iron 10 bolted or otherwise secured thereto, one flange of which projects 80 to the rear flush with the outer edge of the door. When the door is closed inner edge *b'* engages angle-iron 10 and thus not only draws the door closely against the door-post, but seals the joint between the same. 85

The vertical strip *c* protecting the forward edge of the door is Z-shaped in cross-section and its outer flange is secured to the outer margin of the said forward edge; its inner flange projects forward from said 90 edge flush with the vertical plane of the inner side of the door and its web connecting these flanges engages and protects the front edge of the same.

The upper edge of the door is also protected. The metal strip *d* employed for this purpose is substantially S-shaped in cross-section; its lower flange laps against the upper outer marginal surface of the door; its horizontal web protects and engages the upper edge of the door, and the structure thereof projecting above the door forms a horizontal runway the open side of which faces outwards.

As hereinbefore stated the corners of the 105 door are protected by triangular corner

plates. The vertical and horizontal edges of plates A and B align with the webs of strips c and d that protect the forward and top edges of the door and with the webs of strips b and d protecting the rear and top edges of the same, and these vertical and horizontal edges are flanged inwards and protect the adjacent vertical and horizontal edges of the door. The angles of these corner-plates 5 to that of door-strip d for the top of the door, and the upper outwardly projecting horizontal flange of strip d enters the runway of strip 12 and interlocks with and travels longitudinally in the same. 70

10 A and B formed by the meeting of the vertical horizontal and hypotenuse edges thereof are truncated, and the ends of the binding strip d of the door, and the upper ends of the binding strips b and c thereof engage 15 any may form a butt joint with said truncated angles, but I prefer to extend the ends of these strips under said plates and to mortise them at the corners.

15 The lower corners of the door are each 20 provided with corner-plates C and D, respectively, that are preferably, made of cast metal, the angles at the ends of the hypotenuse edge being truncated. These plates have their vertical and horizontal edge portions 25 built outwards to form ridges, the inner sides of which are grooved for the reception of the ends of the strip a and the lower ends of the vertical edge strips b and c, of the door. The area or web bound by these 30 ridges and the hypotenuse edge of said plates is depressed and comes in direct contact with the outer surface of the door, and the outer edges of said strips are flanged inwards and lap against and protect the adjacent edges 35 of the door at its corners.

40 The vertical flanged edge of the forward corner-plate C is angle-shaped in cross-section, and corresponds in dimensions to the similar portion of the vertical Z-shaped door-strip e and constitutes a continuation of the same.

45 When the car door is closed the flange of strip e projecting forward therefrom passes back of the outer flange of a vertical Z-shaped metal jamb-strip 11 that is secured to the outer edge of the door-post of door-frame 7. This strip 11 has its inner flange secured in a rabbeted portion of the outer surface of the door post and the outer flange 50 projects toward the door and is held out from said surface so as to provide a vertical channel into which the forwardly projecting flange of the door enters when the latter is closed. The jamb or stop strip 11 is braced 55 against the thrust of the door by brackets 11'.

60 Above the upper edge of the door a substantially S-shaped horizontally disposed overhead metal strip 12 is placed the upper flange of which is secured to the fascia of the car, and the portion below said upper flange projects outwards, then downwards and then inwards to form a channel or runway, the open side of which faces inwards. 65 The cross-section of this strip 12 corresponds

75 Strip 12 extends from a point at or adjacent to the upper left hand corner of the doorway a distance corresponding to the length of the door plus the length of its movement. The upper lefthand corner of said doorway is covered and protected by a triangular shaped shield or corner pocket E. The vertical and horizontal edges of this shield align with the upper edges of the overhead strip 12, and the vertical edge of 80 jamb-strip 11 farthest from the doorway. The marginal portions of the shield adjacent these edges are secured to the outer surfaces of the upper flange of the overhead-strip and the flange of the jamb-strip secured to the 85 door-post and the portion bound by these edges and the hypotenuse edge thereof is raised or stands out from the plane of its vertical and horizontal margins a distance sufficient to cover over the outer flanges of 90 said strips and so that the corner of the door covered by plate A can enter behind it when said door is closed, and be held against the side of the car thereby and protected and shielded so that dust and rain cannot enter 95 the car around said corners.

100 If desired, the shield could be re-enforced by casting a bead g integral with its hypotenuse edge; providing its outer surface with a diagonal fin h extending from the center of length of its hypotenuse edge toward the angle of its vertical and horizontal edges, and providing integral braces k, k, connecting said edges with the sides of the raised part of the shield. 105

105 What I claim as new is:—

110 1. The combination with a car having a doorway, a door-frame therefor having a door-post, a Z-bar secured thereto the outer flange of which projects parallel to the side of the car towards said doorway, and a plate at the upper forward corner of the doorway having depressed vertical and horizontal margins and a raised portion or pocket, of a sliding door the upper forward corner of which enters said pocket when closed, and a Z-bar secured to the forward vertical edge of said door the inner flange of 115 which interlocks with the outer flange of the Z-bar that is secured to the door-post. 120

125 2. The combination with a car having a doorway, a door-frame therefor the outer edge of which projects beyond the side of the car, and comprising a door-post, a Z-bar one flange of which is secured to said door-post and the outer flange of which projects towards said doorway parallel to the side of the car and in spaced relation to said post to provide a channel, and a corner plate having depressed vertical and horizontal 130

edges that are secured to the margins of the upper forward corner of the door-frame and constitutes a pocket, of a sliding door the upper forward corner of which enters said 5 pocket when the door is closed, a Z-bar on the forward edge of the same the forwardly projecting flange of which enters the channel formed by the doorpost and Z-bar and a corner plate secured to the lower forward 10 corner of the door and having a vertical flange alining with the forward flange of the Z-bar secured to the forward edge of the door and likewise interlocking with the outer flange of the Z-bar secured by the 15 door-post when said door is closed.

3. The combination with a car having a doorway, a door-frame therefor the outer edge of which projects beyond the side of the car, a door-post for said door-frame, a Z-bar 20 one flange of which is secured to said door-post and the outer flange of which projects toward said doorway parallel to the side of the car, a horizontal interlocking metal guard secured to the side of the car above the doorway 25 the outer downwardly projecting flange of which overhangs the sliding door, and a corner-plate having depressed vertical and horizontal edges that are secured to the margins of the upper forward corner of the 30 door frame and having a raised portion or pocket, of a sliding door the upper forward corner of which enters said pocket when the door is closed, an interlocking metal shape secured to its upper edge having a flange 35 projecting upwards that interlocks with said guard, a Z-bar on the forward edge of the same the forwardly projecting flange of which engages the outer flange of the Z-bar secured to the door-post, and a corner-plate 40 secured to the lower forward corner of the door and having a vertical flange alining with the forward flange of the Z-bar on the forward edge of said door and likewise interlocking with the outer flange of the Z-bar 45 secured to the door-post when said door is closed.

4. In a railway car, the combination with a door frame, a sliding door and means for supporting the same from the bottom of 50 interlocking means on the upper and leading edges of the door and on the corresponding edges of the door frame and a corner member on said frame in the corner formed by said corresponding edges adapted to extend over a substantial portion of the forward, upper corner of said door when said door is closed.

5. In a railway car, the combination with a door frame of a sliding door having a flange projecting from its forward edge, and an angular member on the corresponding door post of said door frame forming a recess adapted to receive said flange, and a corner member in the upper corner of said door frame extending over and covering 60

the joints between the upper corner of said door and said door frame when said door is closed.

6. In combination with a railway car having a door opening, a door slidable over 70 said opening, and means for supporting said door; an integral metal plate on the upper forward corner of the door secured to the upper and forward edges thereof, and an integral pocket plate at the upper 75 forward corner of the door opening formed with an outwardly offset portion to receive the aforesaid door corner.

7. In combination with a railway car having a door opening, a door slidable over 80 said opening, means for supporting said door from the bottom, and guide means for the upper edge of the door; an integral pocket plate at the upper forward corner 85 of the door opening formed with an outwardly offset portion adapted to receive the corresponding corner of said door.

8. In combination with a railway car having a door opening, a door slidable over 90 said opening, means for supporting said door from the bottom, and guide means for the upper edge of the door; a pocket plate at the upper forward corner of the door opening adapted to receive the corresponding 95 corner of said door, rigidifying metal members along the forward and upper edges of the door and a metal plate on said corner of the door secured to said rigidifying members.

9. In combination with a railway car having a door opening, a door supported so as to be movable over said door opening, rigidifying members on the forward and upper edges of the door, a plate on the forward, upper corner of the door secured to 105 said rigidifying members, and a pocket plate at the upper forward corner of the door opening to receive the corresponding corner of the door.

10. In combination with a railway car 110 having a door opening, a door supported so as to be movable over said door opening, rigidifying members on the forward and upper edges of the door, a plate on the forward, upper corner of the door secured to said rigidifying members, a stop member at the forward edge of the door opening, a guide member on the car above the door opening, and a pocket plate secured to said stop and guide members adapted to receive 115 120 the corresponding corner of the door.

11. In combination with a railway car having a door opening and a door post at the forward side of the door opening the forward outer corner of which is rabbetted 125 to form a recess, a door supported so as to be movable over said door opening, a Z-bar seated in the recess of the door post with its intermediate web projecting outwardly from the side of the car body and bearing 130

against the door post and with one flange web lying against the forward edge surface of the door and one flange secured to the front surface of the door and the other flange forwardly projecting so as to extend under the aforesaid flange on the other Z-bar when the door is closed, a guide member on the car above the door, a corner pocket secured to said guide member and the Z-bar on the car body, a stiffening member on the upper edge of the door and a corner plate on the door secured to said stiffening member and to the Z-bar on the forward edge of the door in position to enter said corner pocket. 25

5 against the door post and with one flange web lying against the forward edge surface of the door and one flange secured to the front surface of the door and the other flange forwardly projecting so as to extend under the aforesaid flange on the other Z-bar when the door is closed, a guide member on the car above the door, a corner pocket secured to said guide member and the Z-bar on the car body, a stiffening member on the upper edge of the door and a corner plate on the door secured to said stiffening member and to the Z-bar on the forward edge of the door in position to 30

10 flange secured to the front surface of the door and the other flange forwardly projecting so as to extend under the aforesaid flange on the other Z-bar when the door is closed. 35

12. In combination with a railway car having a door opening, a door supported so as to be movable over said door opening, a Z-bar near the forward edge of the door opening with its intermediate web projecting outwardly from the side of the car body and one flange extending rearwardly toward the door opening, a Z-bar on the forward edge of the door with its intermediate

In witness whereof I have hereunto set my hand this 15th day of April, 1918.

EDNA BLANKE MURPHY.
